RELIGIOUS STATUE BOX

Jacob A. Dossman, St. Martin, Ohio

Application December 7, 1953, Serial No. 27,955

Term of patent 7 years

(Cl. D29—20)

Fig. 1.

Fig. 2.

To all whom it may concern:

Be it known that I, Rev. Jacob A. Dossman, a resident of St. Martin, Brown County, State of Ohio, have invented a new, original, and ornamental Design for a Religious Statue Box, of which the following is a specification, reference being had to the accompanying drawing, forming part thereof.

Fig. 1 is a perspective view of a religious statue box showing my new design; and, Fig. 2 is a cross sectional view thereof taken along the line 2—2 of Fig. 1.

I claim:

The ornamental design for a religious statue box, as shown.
